[57] CLAIM

The ornamental design for sliding marker for measuring tape, as shown.

DESCRIPTION

FIG. 1 is a top, front, and left side perspective view of a sliding marker for measuring tape showing my new design, the broken line showing of a measuring tape is environmental only and forms no part of the claimed design;

FIG. 2 is a right side elevational view;

FIG. 3 is a top plan view;

FIG. 4 is a rear elevational view; and

FIG. 5 is a bottom plan view thereof.

The fragmentary broken line showing of a measuring tape in relation to the marker in FIG. 1 is not a part of the design.

Fig. 2
